UNITED STATES PATENT OFFICE.

HANS C. HANSEN, OF NEWTON, MASSACHUSETTS.

METAL-EXTRACTOR.

No. 879,870.

Specification of Letters Patent.

Patented Feb. 25, 1908.

Application filed May 4, 1907. Serial No. 371,844.

To all whom it may concern:

Be it known that I, HANS C. HANSEN, a citizen of the United States, residing in Newton, county of Middlesex, and State of Massachusetts, have invented an Improvement in Metal-Extractors, of which the following description, in connection with the accompanying drawing, is a specification, like letters on the drawing representing like parts.

In melting metals, especially combinations of lead, antimony, tin and copper, the dross accumulated on the surface of the molten metal contains a very considerable quantity of valuable metal, a part of which is usually recovered by a refining operation. Appreciating the extent of this loss I have invented an extractor that may be supported on the kettle containing the molten metal and the hot dross applied thereto may be squeezed powerfully, a very large proportion of the metal held in suspension in the dross leaving the latter and entering directly the molten metal.

Figure 1 in perspective shows my novel metal extractor suspended over a melting pot, the extractor being closed; Fig. 2 is a top or plan view of the extractor; Fig. 3 a detail showing the extractor open for the reception of dross, the hand levers being broken off to save space on the drawings; Fig. 4 is a top view of the dross receptacle without its cover.

The dotted lines P represent part of a melting pot which will be set as usual that a flame may act on the pot and melt the metal therein. The extractor to be effective for the purpose designed must be so constructed that great pressure may be exerted on the dross. The dross receptacle A is shown as a metallic box having a series of perforations, and a cover C. The box has an ear a and an extension b. The ear a has a pin that enters an angular portion a^x of a lever a' shown as having a shackle a² with which may be connected a suspending device or chain d when it is de-

sired to hang the extractor from a ceiling as when the extractor should be of large size and heavy to handle, the lower end of the chain terminating a little above the level of the kettle, so that when the levers a', b' are in the position Fig. 1, the extractor may be sustained as to be swung freely above the top of the kettle. The extension b has a stud or pivot b² on which is hung a link b³, the opposite end of which is joined by a pin b⁴ with the short arm b⁵ of the lever b', the levers a' and b' having a common fulcrum in a stud b⁶.

The cover C is sustained loosely by a coupling device e, made as a nut having a partially conical protuberance and turned on to the threaded stem of a cover carrier e' shown as 60 a rod jointed at e² to the lever b³, said carrier being extended through the bottom of the receptacle A, the carrier being bent as shown at e³, to insure the tipping of the cover to one side of the box when the cover is open as 65 shown in Fig. 3, at which time the dross may be so fed into the receptacle, the bent part of the carrier acting on the bottom of the box as the cover is descending, insuring the correct entrance of the cover into the box. 70

When the extractor is to be used, the levers will be opened as shown in Fig. 3, thus lifting the cover from the receptacle, and the latter will be moved to place the same over the molten metal in the kettle A, and preferably the receptacle will be dipped into the metal, it thereby being highly heated, and while the cover is raised from the receptacle a person using a hand-operated skimmer may put the dross into the receptacle, and 80 when sufficiently filled the levers will be closed in the position Fig. 1, causing the cover to enter the receptacle and squeeze the dross very hard thus expressing therefrom the metal held in suspension in the 85 dross, the metal running from the dross into the metal pot. When changing the levers from the position shown in Fig. 3 into the position shown in Fig. 1 great force is exerted, as the parts a^x and b⁵ of the levers a', b' 90 act as toggles united at b⁶.

In practice by the use of my novel extractor I am enabled to make a very considerable saving in metal and the dross is squeezed so hard as practically to remove 95 therefrom all the really available metal. When the cover is drawn into the receptacle, the latter is substantially at rest with the curved part a^x of the lever a' on the top of the kettle or its setting. 100

In my invention the dross enters the receptacle while yet resting on the top of the molten metal. I am not aware that dross of melting pots has been so fed directly from the top of molten metal into an extractor, 105 the latter being heated by the molten metal and the hot dross squeezed while the extractor is in position over the melting kettle.

The described method of squeezing dross is I believe novel. This invention is not to 110 be limited to the exact shape shown for the levers, or the connection between said levers

and the receptacle and cover, as these parts might be varied in construction and yet be able to exert powerful pressure on the dross in the receptacle and yet not depart from 5 my invention as hereinafter broadly claimed.

Having fully described my invention, what I claim as new and desire to secure by Letters Patent is:—

1. A metal extractor comprising a receptacle and a cover to enter the same, and two crossing levers, one pivoted on the other between the ends of said levers, one lever being operatively connected with said receptacle and the other with said cover, the movement 10 of said levers about their common pivotal point causing the coaction of the cover with said receptacle to express the liquid metal from the dross.
2. A metal extractor comprising a receptacle, a cover to enter said receptacle, two levers, one pivoted on the other, each lever having an extension at its inner end, and means to connect the extension of said levers respectively to said receptacle and said 15 cover.
3. A metal extractor comprising a metallic receptacle, and a cover, a cover carrier, a lever on which said cover carrier is sustained, and two hand-operated crossing 20 levers one pivoted on the other, one lever being operatively jointed to the receptacle and the other to the lever sustaining the cover carrier.
4. A metal extractor comprising a foraminous receptacle having a hole in its bottom, a lever connected therewith, a cover carrier 25

extended from the under side of said receptacle upwardly through the hole in its bottom; and a cover mounted on said carrier.

5. A metal extractor comprising a foraminous receptacle having a hole in its bottom, 40 a lever connected therewith, an offset cover carrier extended from the under side of said receptacle upwardly through the hole in its bottom, and a cover mounted loosely on said carrier.

6. A metal extractor comprising a foraminous receptacle and a cover carrier, a cover mounted loosely thereon, a lever pivoted to said receptacle and sustaining said cover carrier, and two hand levers pivoted one on the other near their inner ends, the inner 45 ends of said levers being pivoted to said receptacle and the other to one end of the lever sustaining the cover carrier, whereby when said levers are closed to draw the cover into the receptacle the inner ends of said hand levers act as toggles.

7. A metal extractor comprising a foraminous receptacle having a hole in its bottom, 60 a connected lever, a cover carrier extended from the under side of said receptacle upwardly through the hole in its bottom, a cover, and means for adjusting said cover on said cover carrier.

In testimony whereof, I have signed my name to this specification, in the presence of two subscribing witnesses.

HANS C. HANSEN.
